RAIL FASTENER

Moses L. Myer, University City, Mo.

Application June 21, 1941, Serial No. 399,129

3 Claims. (Cl. 238—349)

This invention relates to a rail fastener or clip for securing a railway rail to a tie plate.

One of the objects of this invention is to provide a fastener of economical construction, so arranged that the fastener may be readily inserted, tightened and removed, and which will be generally efficient in service.

Another object of the invention is to provide a resilient fastener arranged in such a manner as to dampen the rail wave and thus reduce the tendency to loosen spikes which hold the plate or rail in position on the ties.

A further object of the invention is to provide a fastener which will also act as a rail anchor to prevent or reduce the tendency of rail creeping.

A further object is to provide such a rail fastener which can be used with a standard tie plate, which can be held in engagement in the usual spike hole of such a plate without the necessity of providing or preparing a hole in the tie.

Other objects of the invention are inherent in the device, and may be apparent from the following detail description taken in connection with the accompanying drawing.

Fig. 1 is a plan view with the ball of the rail removed, better to display the novel features of this invention;

Fig. 2 is a vertical section on line 2—2, Fig. 1;

Fig. 3 is a side view of the fastener;

Fig. 4 is an end view; and

Fig. 5 is a perspective view.

A clip or fastener, shown separately in Figs. 3, 4 and 5, is adapted to be secured to a tie plate 1 by being inserted in a usual spike hole 2 in the plate, with a leg engaging the upper surface of the base of a rail 3.

The fastener is shown in connection with a tie plate 1 and a conventional rail 3. The tie plate has a rail seat 4 defined by upstanding shoulders 5. The tie plate, as specifically shown, has two spike holes 2 adjacent the seat 4 and four spike holes 6 through the apron of the tie plate and a substantial distance from the rail seat. A conventional tie plate usually has four holes such as 2 adjacent the seat. In conventional practice, spikes are driven through some of these holes and those which are driven through the holes 2 have their heads engaging the top of the rail base, thus holding the rail in position. With the present practice spikes are driven through the holes 6 only.

The rail fastener embodying the present invention is constructed of a single piece of strip spring material with two legs, an upper leg 7 which engages the top of the rail base and a 55

lower leg 8 which engages in a hole 2 of the plate. These legs 7 and 8 are angularly disposed with relation to each other. As specifically shown, this angle is approximately 60°. The two legs 5 are integral and joined by a curved hump 9 which, as specifically shown, is an arc of a circle comprising approximately 120°. The angularity between the legs and the arc of the hump are not critical and may be changed depending upon 10 the punching of the plate.

The lower leg 8, at least, of the fastener comprises two plies of the strip integrally and resiliently connected and offset from each other. That is to say, an outer ply 10 and an inner ply 11 are offset from each other, and the outer edges 15 are serrated as shown at 12 and 13. The arrangement is such that when the leg 8 is inserted or driven in the hole, the serrated edges 12 and 13 will engage opposite walls of the hole 2, thus holding the clip or fastener in position, while the upper leg 7 engages the base of the rail.

The rail clip preferably is constructed as specifically shown, wherein it consists throughout 25 of a single piece of folded strip of substantially uniform width, folded upon itself with the loop of the fold at the end of the upper leg 7. The fold is made in such a manner that the two plies at the lower leg 8 are offset from each other as previously described.

30 To facilitate driving the fastener into position, the lower ends of the surfaces 12 and 13 are bevelled, as shown at 14 and 15. It will be seen that the clip may be driven in or tightened by tapping upon the hump 9. It will also be understood that the clip may be removed readily by using a tong which will engage the offset surfaces 12 and 13. That is to say, by squeezing together 35 the offset plies in the leg 8 the clip may be removed easily from the assembly.

40 The hump 9 in the form as shown, or its equivalent, is provided for a dual purpose, that of giving a satisfactory surface for driving the clip into position, and for tightening it, and it also provides a spring structure which is effective in dampening the rail wave. As shown in Fig. 3, the two plies may lie close together along the leg 7, whereas in normal conditions they may be separated slightly along the leg 8.

45 From the foregoing description it will be apparent that the invention accomplishes its objects. Various changes may be made in the details of construction, within the scope of the appended claims, without departing from the spirit 50 of this invention.

I claim:

1. A rail clip consisting of a single piece of folded strip spring material, the composite clip thus consisting of two plies of such material having an upper and a lower leg angularly disposed with relation to each other, the end of the upper leg terminating in a loop of the strip material with the free ends of the strip at the end of the lower leg, the folds of the material at the lower leg being offset from each other each fold having an edge extending beyond the adjacent edge of the other and at least one having saw-tooth serrations, such edges being substantially parallel, whereby the serrated edges will engage opposite walls of a hole in a relatively thick portion of a tie plate in which the lower leg is placed while the upper leg engages the upper surface of the base of a rail with a number of serrations engaging the side of the hole and without the end of the lower leg extending substantially below the bottom of the plate.

2. A rail clip consisting of a single piece of folded strip spring material of substantially uniform width throughout, the composite clip thus consisting of two plies of such material, having an upper and a lower leg angularly disposed with relation to each other, the end of the upper leg terminating in a loop of the strip material with the free ends of the strip at the end of the lower leg, the folds of the material at the lower leg being offset from each other each fold having an edge extending beyond the adjacent edge of the

other and having saw-tooth serrations, such edges being substantially parallel, whereby the serrated edges will engage opposite walls of a relatively thick portion of a hole in a tie plate in which the lower leg is placed while the upper leg engages the upper surface of the base of a rail with a number of serrations engaging the side of the hole and without the end of the lower leg extending substantially below the bottom of the plate.

3. A rail clip consisting of a single piece of folded strip spring material to provide a clip of two plies of spring material lying adjacent each other, connected at their upper end by a loop of the material, having the free ends of the plies provided with saw-tooth-like serrations on at least one of opposing substantially parallel surfaces and positioned and proportioned to engage opposite walls of a hole in a relatively thick portion 20 of a tie plate in which the free ends may be inserted; the clip having its upper portion including the loop forming a leg angularly disposed with reference to its lower end forming a leg which includes the free ends of the plies, whereby the upper portion may bear against the base of a rail when the free ends are inserted whereby a number of serrations will engage the side of the hole and without the end of the plies extending substantially below the bottom of the plate in the hole in the tie plate.

MOSES L. MYER.
